UNITED STATES PATENT OFFICE

JOSEPH FETYK, OF NEW YORK, N. Y., ASSIGNOR TO FRANCIS KEIL & SON, INC., A CORPORATION OF NEW YORK

CONSTRUCTION FOR MAIL BOXES

Application filed January 9, 1926. Serial No. 80,161.

This invention relates to construction for mail boxes and with regard to certain more specific features thereof to mail boxes for apartment houses or the like.

One of the objects of the invention is to provide a construction of the above nature which is practical and efficient, capable of meeting the requirements of use in a highly satisfactory manner. Another object is to provide a construction of the above nature which is particularly suited to the convenience of the mail carrier. Another object is to provide a mail box construction in which a plurality of individual private compartments for mail are accessible to the mail carrier through a common door and wherein this door is capable of being locked dependably against intrusion. Another object is to provide such a construction wherein the mail carrier may gain access to the mail compartment or compartments in the instance of the lock having been tampered with or otherwise rendered inoperative. Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawings, in which is shown one of the various possible embodiments of this invention,

Figure 1 is a front elevation of a mail box construction embodying a plurality of private compartments, certain of the compartments being shown only in part and one thereof being broken away to disclose the interior;

Figure 2 is a section taken substantially along the line 2—2 of Fig. 1;

Figure 3 is a section taken substantially along the line 3—3 of Fig. 1;

Figure 4 is a section in larger detail taken substantially along the line 4—4 of Fig. 1;

Figure 5 shows a front elevation of a lock mechanism;

Figure 6 is a section taken substantially along the line 6—6 of Fig. 5, and

Figure 7 is a section taken substantially along the line 7—7 of Fig. 5.

Similar reference characters refer to similar parts throughout the several views of the drawings.

Referring now to Figures 1 and 2 of the drawings in detail, there are illustrated, as best shown in Figure 2, five individual mail compartments 10, 11, 12, 13 and 14, the compartments 11 and 13 being shown only in part. Although the compartments are in this instance shown as five in number, it will be understood that any desired number thereof may be arranged together and assembled as will be described later. These mail compartments are of substantial depth and height, being preferably of such size as to be able to accommodate, for example, newspapers, magazines, and medium sized packages, as well as letters. Each compartment is provided with a front wall 15 which is preferably of a heavier construction than the side and rear walls of the compartments, the sides and rear of each compartment being conveniently formed of a single piece of light sheet metal as is brought out in Figure 2.

Each of the mail compartments is provided in its front wall at the lower portion thereof with a door 16. Each of these doors is provided with an individual lock 17 and is for the use of the owner of the mail compartment in removing mail therefrom.

In addition to the lower doors 16, each of the mail compartments is provided with an upper door 18, these upper doors being adapted for the use of the postman or mail carrier in inserting the mail in the compartments. These doors 18 are secured together as will presently be described to open and close as a unit.

Preferably they are mounted to swing outwardly about their bottom edges as shown in Figure 3, and a single lock 19 positioned upon a central door 18 serves to lock all of the connected doors in closed position. A suitable name-plate 20 is provided on the front wall of each of the individual mail compartments. In addition, and as shown in Figure 1, there is preferably provided within

100

each compartment a suitable holder 21 which contains a card listing the names of additional parties who are to receive the mail in that compartment.

5 Thus the mail carrier by unlocking the single lock 19 is enabled to swing all of the doors 18 to open position as a unit and immediately has access to all of the series of mail compartments. This is a great convenience for the 10 mail carrier and results in a substantial saving of time. The mail carrier alone is furnished a key to the lock 19 whereas the keys fitting the locks 17 of the lower doors 16 are held by the owners or occupants of the apartment or portion of the building served by the 15 particular mail compartment. The doors 16 are preferably provided with perforations 22 and the doors 18 are preferably provided with perforations 23 to permit a view of the interior of the compartments without unlocking and opening the door. Narrow slots 24 may be provided in the doors 18 for the insertion of calling cards, telegrams or the like.

The separate compartments are preferably 25 positioned together so that the front walls 15 of adjacent compartments abut along their side edges and so that thus the front walls as a unit present a substantially solid appearance. Each of the front walls 15 are provided 30 adjacent their side edges with rearwardly projecting lugs 25 as shown in Figures 3 and 4. The compartments are secured together by bolts 26 passing through these registering lugs. Any desired number of the compartments 35 may be arranged side by side and rigidly secured together in this manner.

Each of the doors 18 is provided on either side thereof with a projecting arm or lug 27. As best shown in Figure 2, the doors 18 are 40 secured together to swing as a unit by means of bolts 28 passing through these projecting lugs 27.

The doors 16 and 18 when closed preferably 45 rest substantially flush with the outer surface of the front walls 15. The projecting and connecting lugs 27 of the doors 18 are accommodated in recesses formed in the walls 15 and extending into rearwardly projecting fins 29 as shown in Figures 2 and 4.

50 As has been mentioned above, the doors 18 joined together to swing open as a unit, are provided with a single lock 19 which is positioned upon a central door whereby the mail carrier is enabled to gain access to all of the mail compartments by unlocking a single lock. Also, as has been mentioned, these doors 18 preferably seat into and rest flush with the front walls 15. In order to assist the lock 19 in holding the doors 18 in closed 55 position additional holding means are preferably provided on one or more of the doors 18 on either side of the central door carrying the lock 19. In Figure 4 there is shown a vertical section through the center of the door 60 18 at the extreme right of Figure 1. Refer-

ring to Figure 4, this door is provided on its inner side and adjacent its top edge with a rearward projection 30 in which is carried a suitable pin 31 urged upwardly by a spring 32. This pin is provided with a rounded upper end which takes into a rounded recess 33 formed in a rearward projection 34 on the wall 15. The upper end of the pin 31 registers with the recess 33 when the door 18 is closed and thus serves yieldingly to hold the 75 door in closed position. Similar spring pressed pins are preferably provided on each of the doors 18 except the one carrying the lock 19 or, at least, one of the spring pressed pins is provided for each of the end doors. 80

These spring pressed pins 31 and their co-acting recesses in the front walls 15 of the mail compartments assist the lock 19 in holding the series of connected doors in closed position and they prevent the doors from warping outwardly out of alignment when closed. The proper fitting of the doors into their respective openings and the proper registry of the outer surfaces of the doors with the outer surface of the walls 15 are thus assured. Moreover, these spring pressed pins, yieldingly holding the doors in proper closed position, prevent the possibility of anyone 90 prying the doors open since, by holding the doors flush with the front walls, they preclude the possibility of inserting a screw driver or the like around the edge of the doors. 95

Considering now more particularly the lock 19 positioned, as hereinbefore noted, 100 preferably upon a central door 18 and arranged to lock all of the connected doors 18 in closed position, reference may be had more particularly to Figures 3, 5, 6 and 7. The lock mechanism 19 may be of any suitable 105 construction and preferably includes a casing generally indicated at 35 held in place at the upper end of the inner face of the central door 18 by means of a suitable number of screws 36, conveniently and preferably four 110 in number, threaded into the door from the inner face thereof. The lock casing 35 is of course positioned so that its spring-pressed latch 37 may, when the door 18 is closed, 115 spring upwardly and in back of the rigid upper front wall portion of the compartment. The latch 37 may be operated from the exterior by means of an appropriate key operative through any suitable or appropriate tumbler or other suitable mechanism; the door 18 is therefore provided with an appropriate opening 38, preferably circular through which the key-receiving portion of the lock mechanism may project outwardly. This 120 key-receiving portion of the lock is generally indicated at 39 and is provided with an appropriate key hole indicated at 40.

Each of the screws 36 is threaded into recesses in the door 18, these recesses preferably 125 passing completely through the metal of 130

which the door 18 is made; the free ends of the screws 36 are thus exposed, and each screw 36 has formed therein a longitudinal recess 42, conveniently formed by drilling into the free end of the screw and along the axis thereof. This recess 42 may be of any convenient depth, and is clearly shown in Figure 7.

Upon the exterior of the central door 18 to which the lock 19 is thus secured there is mounted a concealing plate 43 provided with an appropriate aperture to receive the key-receiving portion 39 of the lock 19, this plate 43 being of a sufficient expanse in an upward as well as lateral direction to overlap to an appropriate extent the lock-securing screws 36 (see also Fig. 5). The plate 43 thus effectively conceals the exposed recessed ends of the screws 36 and is securely held to the door 18 by an appropriate number of rivets 44, conveniently four in number.

By means of the lock mounting just above described, the mail carrier may, when the lock 19 is in normal or operative and untampered condition gain access to the several mail compartments, all as hereinabove described. But in practice it has been found that the mail carrier oftentimes finds the lock 19 in a condition such that his master key fails to gain him access to the individual compartments. While this circumstance may arise because of a defect occurring in the lock mechanism, yet this circumstance has been in practice found to arise more frequently by reason of the master lock, and particularly the key hole 40 thereof, having been tampered with, plugged up or otherwise made inoperable by the master key.

Where such a circumstance arises, the complete locking mechanism 19 has to be removed for repair and promptly replaced by a new or operative locking mechanism; the defect may, by virtue of this invention, be readily and speedily remedied, and without substantial delay in the ultimate distribution of the mail, and without destructive action upon the mail box or compartment itself. The concealing plate 43 is first removed and this, it may be pointed out, may be effected speedily and in a simple manner. More particularly, the heads of the rivets 44, illustratively four in number, are knocked off as by means of a chisel and hammer, the removal of the concealing plate thus exposing the recessed ends of the screws 36. The operative delegated to remedy the defect thereupon inserts into the recessed ends of the screws 36, thus exposed on the outer side of the door 18, any suitable small instrument, such, for example, as the small end of a file; by applying a slight pressure to the implement and at the same time giving it a rotary movement, the screws 36 may be unthreaded, and the complete locking mechanism 19, thus unfastened, allowed to drop into the compartment. The doors 18 may thereupon be

opened, the defective lock removed, and promptly replaced by a new or operative locking mechanism, the same screws 36 being used to secure it in place. The concealing plate 43 is then mounted in position again, new rivets, which are headed over upon the inside face of the door 18, being employed. The mail receiving boxes are thus restored for operation by the mail carrier through his master key, it being pointed out that the otherwise necessary procedure, with resultant destructive effects, of drilling out the lock fastening screws from the outside face of the door 18, being completely avoided.

It will thus be seen that there has been provided in this invention an apparatus in which the several objects hereinabove pointed out, together with many thoroughly practical advantages, are successfully achieved. It will be seen that the apparatus is of a thoroughly practical nature and is well adapted to meet reliably and speedily the varied conditions of hard practical use. It will moreover be noted that the many advantages attendant upon the use of a series of individual mail compartments all accessible to the mail carrier by way of a single master key may be effectively realized in practice while such serious disadvantages as may arise out of the necessity of destroying or permanently marring a mail receiving compartment due to the necessity of removing an inoperative lock, are effectively avoided.

As many possible embodiments may be made of the above invention and as many changes might be made in the embodiment above set forth, it is to be understood that all matter hereinbefore set forth or shown in the accompanying drawings, is to be interpreted as illustrative and not in a limiting sense.

I claim as my invention:

1. In construction for mail boxes, in combination, a compartment for mail, a door therefor adapted to be opened by the postman for insertion of mail, a lock mechanism positioned on the inner side of said door and operable by a key from the outer side thereof for releasing said lock, and screws threaded into said door from the inner side thereof and holding said locking mechanism in place upon the inner side of said door, said screws having means accessible from the outer side of said door to permit unthreading thereof and dismounting of said locking mechanism for opening said door in case said lock is found not operable by said key.

2. In construction for mail boxes, in combination, a compartment for mail, a door therefor adapted to be opened by the postman for insertion of mail, a lock mechanism positioned on the inner side of said door and operable by a key from the outer side thereof for releasing said lock, screws threaded into said door from the inner side thereof and

holding said locking mechanism in place upon the inner side of said door, said screws having means accessible from the outer side of said door to permit unthreading thereof and dismounting of said locking mechanism for opening said door in case said lock is found not operable by said key, and removable means normally concealing said last means.

- 10 3. In construction for mail boxes, in combination, a compartment for mail, a door therefor adapted to be opened by the postman for insertion of mail, a lock mechanism positioned on the inner side of said door and operable by a key from the outer side thereof
- 15 15 for releasing said lock, screws threaded into said door from the inner side thereof and holding said locking mechanism in place upon the inner side of said door, said screws having means accessible from the outer side
- 20 20 of said door to permit unthreading thereof and dismounting of said locking mechanism for opening said door in case said lock is found not operable by said key, and a plate member concealing said last means and secured in place so as to be capable of removal by the blow of a hammer or the like.

4. In construction for mail boxes, in combination, a compartment for mail, a door therefor adapted to be opened by the postman for insertion of mail, a lock mechanism positioned on the inner side of said door and operable by a key from the outer side thereof, and screws threaded into said door from the inner side thereof and holding said locking mechanism in place upon the inner side of said door, said screws projecting through to the outer side of said door and having their outer ends recessed for the insertion of an implement to unthread said screws from the outer side of said door thereby dismounting said locking mechanism and permitting opening of said door by the postman in case said lock is found not operable by said key.

- 45 5. In construction for mail boxes, in combination, a compartment for mail, a door therefor adapted to be opened by the postman for insertion of mail, a lock mechanism positioned on the inner side of said door and operable by a key from the outer side thereof, screws threaded into said door from the inner side thereof and holding said locking mechanism in place upon the inner side of said door, said screws projecting through to the outer side of said door and having their outer ends recessed for the insertion of an implement to unthread said screws from the outer side of said door thereby dismounting said locking mechanism and permitting opening of said door by the postman in case said lock is found not operable by said key, and removable means normally concealing the outer ends of said screws.

6. In construction for mail boxes, in combination, a compartment for mail, a door

therefor adapted to be opened by the postman for insertion of mail, a lock mechanism positioned on the inner side of said door and operable by a key from the outer side thereof, to permit said door to be opened, means securing said lock mechanism in place upon the inner side of said door, said securing means being releasable and extending to the outer side of said door, a plate member of less 70

expansive than said door but of sufficient ex-
panse to cover said securing means on the outer side of said door, and means mounting said plate member in covering position and capable of removal as by the blow of a ham-
mer or the like.

In testimony whereof, I have signed my name to this specification this 23rd day of December, 1925.

JOSEPH FETYK.
